PLUNGER PUMP

Ernst Schaeren, Solothurn, Switzerland, assignor
to Scintilla Aktiengesellschaft, Solothurn,
Switzerland

Application September 3, 1932, Serial No. 631,700
In Germany September 18, 1931

4 Claims. (Cl. 103—227)

The invention relates to plunger pumps the suction and pressure channels of which are controlled by slide valve gears, and the working plunger and the slide valve of the same being arranged in parallel to each other, but set apart from one another at an angle of 90° in the cycle of operation.

In plunger pumps of this kind as hitherto known the working plungers and the slide valves are operated by means of two driving discs obliquely disposed with respect to the axis of rotation or by means of a separate eccentric for each member. In the case of the former type of pumps a high relative speed of the driving disc to the adjustable member of the plunger takes place, resulting in a rapid wearing of these parts and causing the adjustable screws limiting the stroke of the plunger to become loose. Apart from this these discs are expensive to manufacture. With the latter type of pumps, considerable space must be allowed for in the axial direction, as the eccentrics for the working plunger and the slide valve are separately disposed side by side; and as the eccentric and the lever provided for the operation of the plunger touch each other, but in a line, high specific pressures are set up resulting in a rapid wear of these members.

According to the present invention the working plungers and the slide valve provided per pump cylinder are driven off a common closed eccentric.

In the drawing a constructional example of the subject of the invention is illustrated.

Fig. 1 is a section of the pump on the line M—N of Fig. 2.

Fig. 2 is a longitudinal section of the pump on the line A—B—C—D and on the line E—F of Fig. 1.

Fig. 3 is a further constructional example of the pump.

In the figures *a* is the pump body, which is screwed on to the side wall of the pump housing *x*. *b* is the working plunger and *c* the slide valve. *d* represents the suction channel and *e* the pressure channel. *f* is a lever pivotally mounted on the fixed pin *k* imparting an axial movement to the working plunger *b*. By means of the screw *q* which is locked by the screw *r* in the lever *f*, the axial play between the working plunger *b* and the lever *f* is adjusted. The lever *f* is turned by the double armed eccentric lever *g* connected to the former by means of the pin *l*. The double armed lever *g* forms a closed ring around the eccentric *h* which is keyed to the shaft *i*. The double armed lever *g* has a pin *m* on the

opposite side of the lever *f*, engaging a slot of a crank lever *n*. The crank lever *n* is pivotally mounted on the fixed pin *p* imparting the necessary axial movement to the slide valve *c*. The shaft *i* is driven off the shaft *u* by means of the gears *s*—*t* and said shaft *u* in its turn is rotated by the lever *v* which is coupled to the shaft *u* in a known manner, by way of example, using a ratchet wheel.

The drive of the working plunger and the slide valve is made, as known, in such a way that in the change of stroke of the working plunger when the speed is reduced to nought, the sleeve valve is approximately in the middle of its stroke having the maximum speed, i. e. the periodical movements of the working plunger and the sleeve valve are set apart from one another at an angle of 90° in the cycle of operation. This is necessary in order that the moment the suction channel is closed, the pressure channel is quickly uncovered, thus preventing an inadmissibly high increase of pressure in the pump chamber *o* during the first part of the pressure stroke. According to the invention both pistons are set apart in the cycle of operation by means of a single eccentric in connection with a crank lever and in order to obtain a displacement of 90°, the condition must be fulfilled in the dead centre of the working piston, that the points *G*—*H*—*I*—*K* and *L* are lying in one straight line, *G* being the centre of the pin *l*, *H* the one of the eccentric *h*, *I* the centre of the shaft *i*, *K* the one of the pin *m* and *L* the one of the pin *p*.

If the fulcrum *L* of the crank lever *n* is not lying on this line, the maximum speed of the sleeve valve would not coincide with the position of the working plunger in the dead centre; in this case the speed imparted by the eccentric lever *g* to the crank lever *n*, directed in the dead centre of the working plunger rectangularly to the said straight line and having a maximum value, would not be fully imparted to the crank lever, but with a smaller component only.

In the position shown in Fig. 1 the working plunger starts its downward stroke whilst the sleeve valve is moving upwards with maximum speed uncovering the channel *e'*. The liquid enclosed in the pump chamber *o* is then delivered through the channel *e'* and via the recess *w* of the sleeve valve to the pressure channel *e*. When the working plunger has reached its lowest position and delivered all the liquid out of the chamber *o*, the sleeve valve has returned again to the position illustrated in Fig. 1, i. e. closes again the channel *e* and connects the suc-

tion channel *d* with the pump chamber *o*. The working plunger moves upwards and the pump chamber *o* is filled up with liquid until the plunger has reached again the position of Fig. 1. 5 The suction channel is again shut off and the cycle of operation is repeated as described above. The sleeve valve *c* by having a recess *w* works as a balanced piston, thereby reducing the pressure on the crank lever *n* practically to nought; 10 the result thereof is that the wear on the sliding parts of the piston and the lever and the pin *m* is diminished. On the other hand the movement of the screw *q* relative to the piston *b* is small; and further the pin *l* and the eccentric *h* 15 are enclosed all around by the eccentric lever *g* with the result that the specific pressure between these parts engaging one another and consequently the wear too is very small. Because of the crank lever *n* a second eccentric is not necessary beside that for the working plunger as used in well known arrangements and therefore the overall length of the pump is reduced by 20 half the amount.

Another constructional example according to 25 the invention is given by an arrangement in which on the right and left hand side of the eccentric lever *g*, a pump body *a* comprising a working plunger and a sleeve valve is provided. This example is shown in Fig. 3. In this arrangement the levers *f* and *n* are disposed symmetrically with respect to the line *k*—*p* and likewise the pump bodies *a* with respect to the same line.

A further advantage of the application compared with known arrangements is the ease with 35 which the pump housing and drive mechanism can be dismounted. As the pump bodies *a* are screwed to the side wall of the pump housing, the pump bodies together with the pistons and its drive members can easily be taken out after 40 having unscrewed the screws without loosening the connections of the pressure pipes.

What I claim is:

1. In a plunger pump in combination a pump 45 casing, pump cylinders, working plungers and sleeve valves, the latter being set apart from one another with respect to their periodical movements at an angle of 90° in the cycle of operation, one working plunger and one sleeve valve at least being arranged per pump cylinder, a common eccentric per pump cylinder, a two 50 armed eccentric lever, a one armed lever, a crank lever, these two latter levers pivotally fixed to the pump casing, a pin fixed to one arm of said eccentric lever for the drive of said working plunger, a pin fixed to the second arm of said 55 eccentric lever for the drive of said sleeve valve, these two pins being arranged diametrically opposite one another with respect to the centre of the bore of said eccentric lever, one of said pins adapted to drive the working plunger being guided in a circle, the other pin engaging said 60 crank lever for the drive of said sleeve valve.

2. In a plunger pump in combination a pump 65 casing, pump cylinders, the latter being screwed to the inside wall of said pump casing, pressure pipe connections disposed in the pump casing proper, working plungers and sleeve valves, being set apart from one another with respect to their 70 periodical movement at an angle of 90° in the cycle of operation, one working plunger and one sleeve valve at least being arranged per pump cylinder, a common eccentric per pump cylinder, a two armed eccentric lever, a one armed lever, a crank lever, these two latter levers pivotally 75 fixed to said pump casing, a pin fixed to

one arm of said eccentric lever for the drive of said working plunger, a pin fixed to the second arm of said eccentric lever for the drive of said sleeve valve, these two pins being arranged diametrically opposite one another with respect to the centre of the bore of said eccentric lever, one of said pins adapted to drive the working plunger being guided in a circle, the other pin engaging said crank lever for the drive of said sleeve valve.

3. In a plunger pump in combination a pump casing, pump cylinders, the latter being screwed on to the inside wall of said pump casing, pressure pipe connections disposed in the pump casing proper, working plungers and sleeve valves being arranged parallel to each other and set apart from one another with respect to their periodical movement at an angle of 90° in the cycle of operation, one working plunger and one sleeve valve at least being arranged per pump cylinder, a common eccentric per pump cylinder, a two armed closed eccentric lever, a one armed lever, a crank lever, these two latter levers pivotally fixed to said pump casing, said common eccentric being disposed between said one armed lever and said crank lever, said working plunger which is slidably connected to said one armed lever and said sleeve valve which is slidably connected with said crank lever, being arranged nearly above one another, a pin fixed to one arm of said eccentric lever for the drive of said working plunger, a pin fixed to the second arm of said eccentric lever for the drive of said sleeve valve, these two pins being arranged diametrically opposite one another with respect to the centre of the bore of said eccentric lever, one of said pins adapted to drive the working plunger being pivotally connected to said one armed lever, the other pin engaging a slot in one arm of said crank lever for the drive of said sleeve valve.

4. In a plunger pump in combination a pump casing, pump cylinders, the latter being screwed on to the inside wall of said pump casing, pressure pipe connections disposed in the pump casing proper, working plungers and sleeve valves being arranged parallel to each other and set apart from one another with respect to their periodical movement at an angle of 90° in the cycle of operation, one working plunger and one sleeve valve at least being arranged per pump cylinder, a common eccentric per pump cylinder, a two armed closed eccentric lever, a one armed lever, a crank lever, these two latter levers pivotally fixed to said pump casing, said common eccentric being disposed between said one armed lever and said crank lever, said working plunger which is slidably connected to said one armed lever and said sleeve valve which is slidably connected with said crank lever, being arranged nearly above one another, a pin fixed to one arm of said eccentric lever for the drive of said working plunger, a pin fixed to the second arm of said eccentric lever for the drive of said sleeve valve, these two pins being arranged diametrically opposite one another with respect to the centre of the bore of said eccentric lever, one of said pins adapted to drive the working plunger being pivotally connected to said one armed lever, the other pin engaging a slot in one arm of said crank lever for the drive of said sleeve valve.
